UNITED STATES PATENT OFFICE.

SIDNEY OWEN, OF PHOENIX, ARIZONA.

FRAMING TOOL AND BEVEL PROTRACTOR.

Application filed July 9, 1925. Serial No. 42,469.

The present invention relates to a framing tool, and bevel protractor, and has for its principal object to provide a structure of this nature which is efficient in enabling one to obtain the angle of bevel for each end and at the same time obtain the length of any brace, rafter, purline, beam, strut, or the like, by adjusting the tool to the actual position of the proposed brace, etc. then transferring the tool to the stick from which the brace, etc. is to be cut by placing the tool on the stick and scribing, or marking across the ends.

Another important object of the invention is to provide protractor heads which may be adjusted in one plane for plain work or may be adjusted in two planes, or both directions, for the purpose of marking jack rafters, hip and valley rafters, oblique braces, or braces which are to fit in between timbers that are warped, crooked, or twisted.

Another object of the invention is to provide a special attachment with adjustable wings to replace one of the protractors for the purpose of marking braces to fit in corners, of any angle, acute or obtuse.

Another important object of the invention is to provide a tool of this nature which is exceedingly simple in construction, easy to manipulate and adjust, reliable and efficient in use, not likely to easily become out of order, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is an elevation of the tool showing the same used to take the measurements for a proposed brace between two angularly disposed members.

Figure 2 is a similar view showing the same applied to the stick from which the brace is to be cut.

Figure 3 is a plan view of the upper portion of the device as shown in Figure 1.

Figure 4 is an enlarged section taken substantially on the line 4—4 of Figure 1.

Figure 5 is a detail section taken on the line 5—5 of Figure 4.

Figure 6 is an elevation of the tool with an attachment on one end thereof in place

of one of the protractor heads so that a measurement may be taken for a brace in a corner,

Figure 7 is a transverse section taken substantially on the line 7—7 of Figure 6.

Figure 8 is a detail perspective view of a straight edge which may be used with the protractor heads in scribing, and

Figure 9 is a detail view showing the application of the straight edge.

Referring to the drawing in detail it will be seen that the shank of the tool includes a pair of rods 5 and 6, one of which has a bolt 7 projected therethrough which extends through an elongated slot 8 provided in the other member. This bolt 7 has a suitable nut (not shown) associated therewith whereby the members 5 and 6 may be held in different adjusted positions in respect to each other so as to vary the length of the shank as may be desired. It is preferable to construct the member 6 with longitudinally extending rectangularly disposed edge flanges 70 75 10 in between which is received the member 5.

A protractor head 11 is pivoted on the end of the member 6 by means of a bolt 12 which may be tightened for holding the head 11 at different angles in respect to the shank. Another protractor head 13 is pivoted on the end of the member 5 by means of a bolt 14 which may be tightened by means of the nut 15'. The protractor head 13 is provided with pin extensions 15 disposed in opposite directions which rotatably receive the sleeves 16 of a straight edge plate 17. Thus the plate 17 may be rotated in different angles in respect to the head 13. A bolt 18 passes transversely through one of the sleeves 16 as is clearly shown in Figure 5, and the head thereof is rested in a seat 19 so as to frictionally engage the adjacent pin 15, so that by tightening up on the nut 20, the bolt head 18 will bind into engagement with the pin 15, and hold the plate 17 at any desired adjusted angle.

By removing the bolt 14, the head 13 may be removed from the shank, and a protractor indicated generally by the letter A may be substituted therefor as is indicated in Figure 6. Referring particularly to this protractor A, it will be seen that the numeral 22 indicates a shank which is provided with right angularly disposed flanges 23 at its longitudinal edges for straddling the shank, and particularly the member 5 thereof as is

clearly indicated in Figure 7, so that when the bolt 14 is placed through the opening in the member 5, and through the shank 22, said shank 22 is held in fixed alignment with 5 the member 5. The shank 22 is provided with an elongated slot 24 extending longitudinally thereof. A pair of straight edge wings 25 are pivoted to the end of the shank 22 as at 26. Links 27 are pivoted adjacent 10 the ends of the wings 25, and are provided with elongated slots 28 so that a bolt 29 may be passed therethrough and through the slot 24, so that when the nut thereof is loosened, the wings 25 may be adjusted to different 15 angles in respect to each other, depending upon the angle of the corner, such as is indicated in Figure 6, and then the nut tightened, and thus the wings are held in this angle.

It is thought that one example of the use 20 of the tool will be sufficient to set forth its utility to those skilled in the carpenter art. As shown in Figure 1, the tool is placed in the exact position of the proposed brace or strut. The tool is then taken away and 25 placed on the stick as is shown in Figure 2, so that by scribing along the straight edges of the protractors 11 and 13, the stick may be cut so as to form the brace or strut for fitting in the position of the tool as it is shown 30 in Figure 1. The adjustability of the plate 17 in relation to the protractor head 13 takes care of any bevel which may be provided in one of the members, and thus by placing the tool on both sides of the stick, this bevel 35 may be cut on the brace or strut. The device is used in the same manner in connection with a corner as shown in Figure 6, except that the protractor 13 is taken off, and the protractor A substituted therefor.

40 With reference particularly to the straight edge 30 shown in Figures 8 and 9, it is desired to point out that the lower end of a jack rafter fits on the wall plate of a building, while the upper end of a jack rafter 45 fits in the hip rafters. Also, the lower end of a jack rafter is at right angles to the wall

plate, while the upper end of a jack rafter is at an angle with the hip rafter, both vertically and horizontally; therefore, while the bottom end is angular on one edge and 50 square across the other edge, whereas in the case of the upper end it is angular in both directions; hence the straight edge is provided to give the top line of the jack rafter, as clearly shown in Figure 9, which is parallel to the top edge of the hip rafter. The straight edge is attached to the plate 17 as at 31 by means of a bolt or any other suitable fastening device which may be passed through one of the slots 32. 55

It is thought that the construction, utility, operation, and advantages of the invention will now be clearly understood by those skilled in this art. The present embodiments of the invention have been disclosed merely by way of example, and in practice attains the various features of advantage enumerated as desirable in the statement of the invention, and the above description. It will be apparent, however, that numerous 70 changes in the details of construction, and in the combination and arrangement of parts may be resorted to without departing from the spirit or scope of the invention as herein-after claimed or sacrificing any of its advantages. 75

Having thus described the invention, what I claim as new and desire to secure by Letters Patent is:—

A tool of the class described including an 80 adjustable shanks, heads pivoted on the shank, means for holding the heads at different angles to said shank, a plate, means for rotatably mounting the plate on one of said heads, and means for holding the plate at 85 different angles in relation to said last mentioned head, the axis of rotation of the plate being in a plane at a right angle to the axis of rotation of the head on which said plate is mounted. 90

In testimony whereof I affix my signature. SIDNEY OWEN.
